US0D1010776S

(12) **United States Design Patent** (10) **Patent No.:** **US D1,010,776 S**
(45) **Date of Patent:** **** Jan. 9, 2024**

(54) **FEMALE QUICK-CONNECT CONNECTOR**

(71) Applicant: **JOI Holding LLC**, Boaz, KY (US)

(72) Inventor: **Jason Ingram**, Boaz, KY (US)

(73) Assignee: **JOI Holding LLC**, Boaz, KY (US)

(**) Term: **15 Years**

(21) Appl. No.: **29/810,118**

(22) Filed: **Oct. 1, 2021**

(57) **CLAIM**

What is claimed is the ornamental design for a female quick-connect connector, as shown and described.

DESCRIPTION

FIG. 1 is a top front right perspective view showing the female quick-connect connector of Applicants' invention. FIG. 2 is a top rear left perspective view of the female quick-connect connector of FIG. 1.

FIG. 3 is a top plan view of the female quick-connect connector of FIG. 1, the bottom plan view being an identical mirror image thereto.

FIG. 4 is a front elevation view of the female quick-connect connector of FIG. 1, the rear elevation view being an identical mirror image thereto.

FIG. 5 is a left side elevation view of the female quick-connect connector of FIG. 1; and,

FIG. 6 is a right side elevation view of the female quick-connect connector of FIG. 1.

The broken lines in the figures are used to represent subject matter that forms no part of the claimed design.
